FREDERICK FRANCIS GREENWOOD, OF HORNSEY, ENGLAND.

Letters Patent No. 97,909, dated December 14, 1869; patented in England, September 16, 1868.

IMPROVEMENT IN BUCKLES.

The Schedule referred to in these Letters Patent and making part of the same.

To all to whom it may concern:

Be it known that I, FREDERICK FRANCIS GREENWOOD, of Hornsey, in the county of Middlesex, England, gentleman, a subject of the Queen of Great Britain, have invented or discovered new and useful Improvements in Fastenings in the nature of "Buckles," and I, the said FREDERICK FRANCIS GREENWOOD, do hereby declare the nature of the said invention, and in what manner the same is to be performed, to be particularly described and ascertained in and by the following statement thereof; that is to say—

My invention consists in the construction of a "lock-buckle," that is to say, a buckle, the tongue of which shall be capable of being locked upon or into its frame.

This invention I prefer to carry out in the following manner:

I combine the frame of a buckle (or three sides of it) with the frame or box of a lock, so that the whole shall form one piece.

Beyond and raised above that part of the buckle which receives the free end of the tongue, when it is closed down, I form a bow-shaped bar or loop or ring or shoe; or, with the same intention, I make a hole in that part of the buckle to receive the tongue at pressure.

The base of the tongue I hinge upon the bolt of the lock, or I form the base of the tongue and the bolt of the lock into a hinge; in other words, the tongue is to be part of the bolt, and is to be discharged and withdrawn with it, or as part of it.

At the end of the frame, opposite the loop or bow with which the tongue engages, I construct a second loop, having a bar, with which the end of the strap, to which the buckle is secured, engages.

When the bolt-tongue is discharged from the lock, I thrust the further or free end of it under the bow-shaped bar, loop, ring, or shoe, or into the hole aforesaid, the intention being that the strap or other article, which the buckle fastens, shall not be released (except by violence) until the tongue of the buckle is withdrawn.

The protrusion and withdrawal of the bolt-tongue may be accomplished either by the use of a separate key, or by means of mechanism appertaining to and inseparable from the lock-buckle itself, and the lock-portion of the arrangement may, as in ordinary locks, work by means of a key, or as in letter-locks and secret locks, the lock-bolt may be released, by setting parts of the lock itself to prearranged positions.

The use of the lock-motion is in all cases to fix the bolt-tongue of the buckle in or upon the frame, which, as aforesaid, is the object of the invention, and this object may obviously be accomplished by bringing the control of the lock to bear upon any part of the bolt-tongue.

Description of the Drawings.

Figure 1 shows a lock-buckle made according to my invention, in which the hinge on which the tongue

turns, forms part of the bolt of the lock, so that when the bolt is drawn into the lock-case by the key, the tongue is stopped from turning on its hinge. The tongue is thus locked down upon the loop of the frame of the buckle, and the buckle cannot be opened except by protruding the bolt by means of the key.

Figure 2 shows a modification of the lock-buckle shown in fig. 1.

In this lock-buckle, the bar which forms the loop at the end of the frame, instead of being a simple bar, as in fig. 1, is made thicker, and has a flange on one side, and a hole in the centre of the end, into which the tongue *c* is shot by the key, thus securely locking the tongue into the frame of the buckle.

To open it, the bolt must be lowered by the key, thus clearing the end of the tongue from the hole in which it was confined. When in this position, the tongue can be turned on its hinge as in the case of ordinary buckles.

Figure 3 shows a buckle in which the tongue does not turn on a hinge at all, but forms the bolt of the lock, and is shot up by the key into a hole in the bar forming the loop at the end of the buckle.

Figure 4 shows a buckle in which the tongue is simply a spring-bolt, moved by mechanism appertaining to the lock itself, which spring-bolt can be locked upon the frame or not, at pleasure.

In each of the forms represented in all the said figures, the frame of the buckle is constructed with a second loop at the end opposite that with which the strap engages, this second loop being for the purpose of enabling the buckle to be conveniently secured to the strap.

Having thus described the nature of my invention, and the manner of performing the same, I would have it understood that what I claim, is—

The combination of the lock, the buckle-frame having a loop at one end for engagement with the tongue, and the movable tongue, in such manner that the lock is fixed to the buckle-frame, and the tongue is held in engagement with the loop by the action of the lock, as before represented and described.

Also, the combination of the buckle-frame, constructed with a loop at one end, for engagement with the tongue, and a second loop at the other end, for engagement with the strap, a lock fixed to said frame between the said two loops, and a tongue engaging with the first of said loops, and controlled by said lock, as before described.

Also, the combination of the buckle-frame, the lock fixed thereto, and the tongue connected with the bolt of said lock by a hinge, so that the said bolt may be turned from and toward the loop of the buckle-frame when not secured by the lock, as before described.

FREDERICK FRANCIS GREENWOOD.
